[57] CLAIM

The ornamental design for a wood-burning heater and fireplace, substantially as shown and described.

DESCRIPTION

FIG. 1 is a perspective view of a wood-burning heater and fireplace, showing our new design;
FIG. 2 is a front elevational view thereof;
FIG. 3 is an end elevational view thereof;
FIG. 4 is a top plan view thereof;
FIG. 5 is a bottom plan view thereof;
FIG. 6 is a rear elevational view thereof.
